UNITED STATES PATENT OFFICE.

FREDERICK JACOB, OF NEWARK, NEW JERSEY.

SEWING-MACHINE.

SPECIFICATION forming part of Letters Patent No. 230,020, dated July 13, 1880.

Application filed March 24, 1880. (No model.)

To all whom it may concern:

Be it known that I, FREDERICK JACOB, a citizen of the United States, residing at Newark, in the county of Essex and State of New Jersey, have invented new and useful Improvements in Sewing-Machines, of which the following is a specification.

This invention consists in a novel mechanism for operating the feed-dog and the shuttle-carrier of a sewing-machine, and the construction and arrangement of the same will be fully hereinafter described in detail.

This invention is illustrated in the accompanying drawings, in which Figure 1 represents a sectional side view of a sewing-machine embodying my invention. Fig. 2 is an inverted plan of the same. Fig. 3 is a transverse section in the plane $x x$, Fig. 1. Fig. 4 is a similar section in the plane $y y$, Fig. 2. Fig. 5 is a transverse section of the oblique cylinder and the fork.

Similar letters indicate corresponding parts.

In the drawings, the letter A designates the main shaft of a sewing-machine, which has its bearings in a bracket-arm, C, rising from the cloth-plate B, and serves to impart to the needle-slide the required reciprocating motion. On the shaft A is firmly mounted an oblique cylinder, D, which serves to impart an oscillating motion to the vertical rock-shaft E. For this purpose said rock-shaft is provided at its upper end with a fork which consists of two broad tines, $a a$, bearing close upon the opposite sides of the oblique cylinder D. In this cylinder is formed a circular groove, b, which is situated in a plane at right angles to the main shaft A, and between the tines $a a$ rises a pin, c, (see Fig. 5,) which engages with the groove b and retains the rock-shaft E in its vertical position. The foot of this vertical rock-shaft turns in a hole in the cloth-plate, and extends through this hole far enough to receive an arm, F, and a lever, G, to which latter is affixed the shuttle-carrier H.

The arm F is firmly connected to the rock-shaft, and it is connected to the lever G at about the middle of said lever by means of a pivot, d, while said lever turns loosely on the bottom end of the rock-shaft.

In the lever G, near to the rock-shaft E, is secured a pin, e, which engages with a slot, f,

in the feed-lever I. This lever is situated beneath the cloth-plate, and it has its fulcrum on a pivot, g, which can move in a slot, h, for the purpose of adjusting the length of the said feed-lever, serving, in connection with a spring, to impart to the feed-dog the well-known four motions, viz: up, forward, down, and backward.

By the action of the pin e and slot f the feed-lever is moved backward and forward, whereby the up-and-down motion of the feed-dog is produced, as will be presently more fully explained. An oscillating motion is imparted to the feed-lever I by means of a lever, J, which has its fulcrum on a pivot, i, Figs. 1 and 3, and is provided at its upper end with a fork, j, that straddles an eccentric, k, on the main shaft A, so that when this shaft is rotated a vibrating motion is imparted to the lever J. The lower end of this lever engages with a slot, l, in the feed-lever I, so as to impart to the same the desired oscillating motion, whereby the feed-dog is moved backward and forward.

For the purpose of moving the feed-dog up and down, the feed-lever is provided with an inclined plane, m, and is held up against the lower side of the feed-dog K by a guide-plate, n, which is secured to the under surface of the cloth-plate. A spring, o, retains the lower side of the feed-dog in contact with the feed-lever, said lower side being provided with a recess which hugs the edges of the feed-lever.

When the feed-lever is drawn back by the action of the pin e on the slot f, the inclined plane m, as it acts on the lower side of the feed-dog, forces the latter up, and when the feed-lever has reached the position shown in Fig. 1 it is caused to swing forward by the action of the lever J, and thereby a forward motion is imparted to the feed-dog. After this motion has been completed the feed-lever is moved forward by the pin e acting on the slot f, and the lower side of the feed-dog rides down on the inclined plane m, being held in contact therewith by the spring o, so that the face of the feed-dog drops below the surface of the cloth-plate, and then a backward motion is imparted to the feed-dog by the action of the lever J on the feed-lever.

By the action of the oblique cylinder on the

- vertical rock-shaft, and by the arm F, which connects this rock-shaft with the shuttle-lever, I am enabled to impart to the shuttle a very rapid motion without noise and without producing any appreciable jar or vibration in the sewing-machine, and by the addition of the eccentric k and lever J the required motions are imparted to the feed-dog in a simple and effective manner.
- 10 I do not claim as new in this application the oblique cylinder and the vertical rock-shaft on which is firmly mounted an arm which carries the shuttle-carrier, such being described in Patent No. 190,047, granted to me April 24, 1877.
- 15 What I claim as new, and desire to secure by Letters Patent, is—
1. The combination, in a sewing-machine, of an eccentric firmly mounted on the main shaft, a lever which receives a vibratory motion by the action of the eccentric, a feed-lever acted on by the vibratory lever, a feed-dog connected with the feed-lever, an oblique cylinder which is firmly mounted on the main shaft, a vertical rock-shaft provided with a fork which braces the oblique cylinder, a shuttle-lever loosely mounted on the rock-shaft and having a pin engaging with the feed-lever, all substantially as and for the purpose described.
2. The combination, in a sewing-machine, of a main shaft, an oblique cylinder, and an eccentric, both being firmly mounted on said main shaft, a vertical rock-shaft provided with a fork which straddles the oblique cylinder, a shuttle-lever which is connected to the vertical rock-shaft, a pin secured in said shuttle-lever, 35 a feed-lever having slots f and l, with one of which said pin engages, a vibrating lever which receives its motion from the eccentric mounted on the main shaft and the lower end of which engages with the slot l in the feed-lever, and a feed-dog connected with the latter, all substantially as and for the purpose described.
3. The combination of the main shaft A, oblique cylinder D, eccentric k, vertical rock-shaft E, vibratory lever J, the arm F, mounted on and receiving motion from the rock-shaft, the shuttle-lever G, having a pin, e, the feed-lever I, having an incline, m, and the slots f and l, engaging the pin e and the end of the vibratory lever, the feed-dog K, and the spring 50 o, all substantially as and for the purpose described.
- In testimony whereof I have hereunto set my hand and seal in the presence of two subscribing witnesses.
- FREDERICK JACOB. [L. S.]
- Witnesses:
- CHAS. KRUSE,
E. F. KASTENHUBER.
